UNITED STATES PATENT OFFICE

HARRY B. HULL, OF DAYTON, OHIO, ASSIGNEE, BY MESNE ASSIGNMENTS, TO FRIGID-AIRE CORPORATION, A CORPORATION OF DELAWARE

REFRIGERATING APPARATUS

Application filed December 30, 1927. Serial No. 243,701.

The present invention relates to improvements in refrigerators and more particularly the type of refrigerator having a refrigerating element located within a cabinet and connected with refrigerant circulating apparatus.

One of the objects of the invention is to provide an improved refrigerating element which will require less space in the refrigerator and thus provide more space for the storage of food without impairing the freezing and cooling qualities of said element.

It is another object of the invention to provide a refrigerating element in which means are provided for rapidly freezing substances placed in close proximity thereto and in which other means are provided for cooling the air circulating in the chamber in which the element is located.

It is a further object to provide an improved arrangement for freezing such substances by contact with a portion of the coil system of the element and to insure the cooling and circulation of air within the refrigerator cabinet by passing the air through another portion of the coil system of said element.

One manner of carrying out these objects is to provide a freezing coil and a cooling coil so arranged that the freezing coil may be placed within a freezing chamber which is out of the direct path of the circulating air and where the cooling coil is disposed in the direct path of the circulating air.

Further objects and advantages of the present invention will be apparent from the following description, reference being had to the accompanying drawing, wherein a preferred form of the present invention is clearly shown.

In the drawings

Fig. 1 illustrates a front view of a refrigerator equipped with the improved refrigerating element;

Fig. 2 is a side view partly in cross-sec-

tion of the portion of the refrigerator containing the refrigerating element;

Fig. 3 shows a front view of the refrigerating element in position in the cabinet;

Fig. 4 illustrates a top view of the element itself; and

Fig. 5 depicts a cut on the line 5—5 of Fig. 4.

Referring in detail to the drawings, the improved refrigerating element comprises a structure adapted for holding trays of substance to be frozen and for cooling and circulating the air within the cabinet. It comprises a portion providing a freezing zone and a portion providing a cooling zone. The freezing zone is indicated by 20 in Fig. 2 and is adapted to contain trays 21 for holding the material to be congealed. These trays are disposed with their bottom in freezing relation to a freezing portion herein shown as a coil 22, which is wound back and forth in a plane parallel to and substantially touching the bottom of the trays. A metal plate 23 may be placed over the coils and the trays placed thereon, suitable slides 24 being placed in the same plane with the member 23. A metal sleeve 25 serves to enclose the trays and the freezing portion or coil 22 to form the freezing zone in which the coil 22 may be secured as by being soldered to the slides 24 above mentioned.

Situated below the freezing zone is the cooling zone whose function is to cool the air circulating in the cabinet. This portion of the element is herein shown as comprising a coil of pipes having a plurality of loops 27 and 28 arranged so as to extend transverse across the axis of the trays.

These loops are composed of two long pipe members of which one, 27, forms the bottom and the other, 28, the top of the loop, the members 27 and 28 being connected by ends 29 and 30. In the preferred embodiment of the invention the top pipe 28 and the bottom pipe 27 are so arranged that they lie in a

vertical plane in which metal fins 31 may be inserted. These fins are attached to the pipes as by soldering to insure good thermal contact. The ends 29 of the coil system may slant as shown in Fig. 2.

5 The sleeve 25 causes air to be directed away from the freezing coil 22 and over the cooling coil. The fins on the pipes 27 and 28 form passage ways adapted to direct the circulating air to the food storage compartment of the refrigerator cabinet.

10 The entire device is enclosed in a metal casing 30^a attached to a portion of the refrigerator cabinet as by screws 31^a. This casing 30^a is provided with openings 32 to provide for the circulation of air into the casing. The bottom of the casing is provided with an opening 33 to provide for the circulation of cold air to the lower portion of the cabinet. The 15 edges of this opening 33 are turned up as at 34 to provide a flange so as to prevent condensed moisture from dripping down into the storage portion of the cabinet, a shield 35 being provided to cover the opening 33 without obstructing the circulation of air.

20 Referring to the refrigerant circulation system of the apparatus the refrigerating medium, for example sulphur dioxide is supplied through a pipe 36 (Fig. 2) from a compressor unit (not shown) located preferably in the upper compartment 40 of the refrigerator cabinet. The refrigerating medium passes through a portion 37 of pipe 36 through a control device such as an expansion valve 38 which regulates the quantity of refrigerant supplied and thence through pipe 39 to the freezing coil 22 above described. This coil is disposed in freezing relation to the trays 21 and the refrigerating medium in 25 expanding therein produces its freezing action in the well-known manner and congeals the substance in the trays.

30 After traversing the freezing coils 22 the refrigerating medium passes through the cooling coil (composed of pipe members 27, 28, 29 and 30) and thence by way of pipe 41 and its extension 42 to the suction end of the compressor.

35 It is apparent therefore that the greatest refrigerating effect is produced in the coil 22 which is adapted to freeze the material in the trays 21 placed thereon or in close proximity thereto, while a lesser refrigerating effect is produced by the cooling coil (composed of pipe members 27, 28 and 30) which serves to cool the storage compartment of the cabinet. While in the preferred embodiment of the invention the difference in the refrigerating effect of the two zones may be effected by 40 connecting the two coils in series or by forming the two coils from a single continuous conduit, it is understood that any suitable means may be used for creating such a difference.

45 A thermostat or the like 43 is placed within the casing 30^a and serves to control the oper-

ation of the refrigerating element in accordance with predetermined conditions within the cabinet, a pipe 44 leading therefrom to suitable compressor control mechanism not shown. The thermostat may be secured in place by any suitable means such as straps 45 or the like.

50 A drain pipe 46 is connected to the bottom of the casing 30^a and serves to conduct away water resulting from condensation or defrosting. A cover plate 47 removably held in place by screws 48 may be placed on the front of the refrigerating element.

55 The improved element may be mounted in a refrigerator cabinet in the well-known manner as by being suspended from a partition or support 49 upon the other side of which the compressor (not shown) is mounted. The structure so produced may be removable and positioned as a unit within the cabinet and rest upon the walls 50 thereof.

60 It is apparent that the refrigerating element described comprises a very compact and shallow structure in which the freezing coils are wound in a horizontal plane and arranged to exert their refrigerating effect upon the greatest available exposed surface of the trays placed upon them. The coil connected in series with the freezing coil or formed integral therewith from a single continuous conduit and provided with fins serves to cool the lower compartment of the refrigerator cabinet by causing the air therein to circulate as shown by the arrows in Fig. 3.

65 By virtue of this construction and arrangement a compact refrigerating element suitable particularly for household cabinets is produced in which the freezing zone is shielded and hence protected from the circulating air and in which the circulating air is directed longitudinally over the loops and through the passageways formed by the fins on these loops downwardly into the food storage compartment of the cabinet. In this manner substances can be congealed rapidly by the freezing zone portion of the apparatus while during the period in which the compressor or refrigerant circulating means is inactive the shielding sleeve surrounding the freezing zone prevents heat exchange between the surrounding air and the interior of the zone so that the congealed substances will be maintained in their frozen state.

70 While the form of embodiment of the invention as herein disclosed, constitutes a preferred form, it is to be understood that other forms might be adopted, all coming within the scope of the claims which follow.

75 What is claimed is as follows:

80 1. A refrigerating element for mechanically refrigerated cabinets, comprising a coil having means for supporting substances placed thereon for congealing, and a coil disposed below said first coil for cooling the air in said cabinet, said first coil comprising con-

- volutions of pipe disposed in a horizontal plane and said cooling coil comprising loops of pipe disposed in a vertical plane, and shielding means for directing the circulation 5 of air over said cooling coil.
2. A refrigerating element for mechanically refrigerated cabinets, comprising a coil having runners for supporting substances placed thereon for congealing, and a coil 10 connected in series therewith below said first coil for cooling the air in said cabinet, said first coil comprising convolutions of pipe disposed in a horizontal plane and said cooling coil comprising loops of pipe disposed in a 15 vertical plane.
3. A refrigerating element for mechanically refrigerated cabinets, comprising a freezing coil adapted for congealing substances placed thereon, and a cooling coil connected 20 in series therewith and disposed below said first coil for cooling the air in said cabinet, said freezing coil comprising convolutions of pipe disposed in a horizontal plane and said cooling coil comprising loops disposed 25 in a vertical plane, said vertical coils being provided with fins.
4. A refrigerating element for mechanically refrigerated cabinets, comprising a freezing 30 coil having means for supporting substances placed thereon for congealing, and a cooling coil connected therewith and having its loops disposed wholly below said freezing coil for cooling the air in said cabinet, and means below the cooling coil for directing 35 the air to be cooled horizontally over the cooling coil.
5. A refrigerating element for mechanically refrigerated cabinets, comprising a freezing coil adapted for congealing substances 40 placed thereon, and a cooling coil connected therewith and having its loops disposed wholly below said freezing coil for cooling the air in said cabinet, and means for shielding the freezing coil from circulating air and 45 for directing the air horizontally over the cooling coil, said means including a shield below the cooling coil.
6. In a mechanically refrigerated cabinet, 50 in combination, a top wall of said cabinet, a refrigerating element including a freezing portion spaced from said top wall, means cooperating with said top wall for providing a freezing chamber containing the freezing portion, and a cooling portion outside of said 55 chamber for cooling the air circulating in said cabinet, and means for directing the circulation of air over said cooling portion.
7. In a mechanically refrigerated cabinet, 60 in combination, a top wall of said cabinet, a refrigerating element including a freezing portion spaced from said top wall, means cooperating with said top wall for providing a freezing chamber containing the freezing portion, and a cooling portion outside of said 65 chamber for cooling the air circulating in said cabinet, and means for directing the circulation of air over said cooling portion.
- said cabinet, said cooling portion being disposed below said freezing chamber, and means for directing the circulation of air over said cooling portion.
8. In a mechanically refrigerated cabinet 70 in combination, a top wall of said cabinet, a refrigerating element including a freezing portion spaced from said top wall, means cooperating with said top wall for providing a freezing chamber containing the freezing portion, and a cooling portion outside of said chamber for cooling the air circulating in said cabinet, said cooling portion being disposed below said freezing chamber and having baffle means adjacent thereto provided with an opening for ingress of circulating air and cooperating with the wall of the freezing chamber for directing air over said cooling portion.
9. A refrigerating element for mechanically refrigerated cabinets, comprising a freezing portion adapted for congealing substances placed thereon, and a cooling coil for 80 cooling circulating air and having the loops thereof extending vertically and disposed wholly below the freezing portion, and means for shielding the freezing portion from circulating air, said means also forming one part of another means for directing circulating air over said cooling coil.
10. A refrigerating element for mechanically refrigerated cabinets, comprising a freezing portion adapted for congealing substances placed thereon, and a cooling coil for 85 cooling circulating air and having the loops thereof extending vertically and disposed wholly below the freezing portion, and means for shielding the freezing portion from circulating air.
11. A refrigerator comprising in combination, a cabinet, a shield within the cabinet to close proximity to an outer wall thereof, a refrigerating element including a portion providing a freezing zone between the shield and said wall, and including a portion providing an air cooling zone on the opposite side of said shield, and means for directing the circulation of air through the cooling zone.
12. A refrigerating element for mechanically refrigerated cabinets, comprising a single continuous conduit formed to provide a freezing portion adapted for congealing substances placed thereon, said continuous conduit also being formed to provide a cooling coil for cooling circulating air and having the loops thereof extending vertically and disposed wholly below the freezing portion, and means for shielding the freezing portion from circulating air.
13. A refrigerating element for mechanically refrigerated cabinets, comprising a single continuous conduit formed to provide a freezing portion adapted for congealing substances placed thereon, said continuous con-

duit also being formed to provide to cooling oil for cooling circulating air and having the loops thereof extending vertically and disposed wholly below the freezing portion, 5 and means for shielding the freezing portion from circulating air, said means also forming one part of another means for directing circulating air over said cooling coil.

In testimony whereof I hereto affix my
10 signature.
